METAL SEAMING TOOL

Quintal A. Paque, Luxemburg, Wis.

Application September 9, 1941, Serial No. 410,215

5 Claims. (Cl. 113—56)

This invention relates to a metal seaming tool, the general object of the invention being to so form and construct the tool that the one tool can be used in forming the single seam and then by slight adjustment the tool can be used for forming a double seam, the device being mainly intended for forming seams in roofing metals.

This invention also consists in certain other features of construction and in the combination and arrangement of the several parts to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is an elevational view of the tool.

Figure 2 is an edge view thereof.

Figure 3 is a fragmentary edge view showing 20 the attachment in operative position.

Figure 4 is a similar view showing the attachment in inoperative position.

Figure 5 is a section on the line 5—5 of Figure 1.

Figure 6 is a section on the line 6—6 of Figure 2.

Figure 7 is a sectional view of the jaws showing the initial step of forming a single seam, and

Figure 8 is a similar view showing the jaws in position for forming a double seam.

In these views the numeral 1 indicates one of the handle members which is formed with an elongated forked part 2 and an elongated transversely extending jaw part 3 has its central portion connected with the lower end of the prongs of this forked part. This jaw part 3 has an arcuate outer edge with its inner edge of stepped formation as shown at 3'. A relatively short shank 4 is located between the prongs of the forked part and has its lower end curving away from the reduced lower end of the forked part and a pivot bolt 5 extends through the lower portions of the prongs of the forked part and through the lower part of the shank and pivotally connecting the shank with the forked part. A jaw forming part 7 of elongated form extends transversely of the shank and has its central portion connected with the curved part 6 of the shank and this jaw part 7 is of substantially angle shape in cross section to provide a part for fitting in the recess formed by the stepped part 3' of the jaw part 3 and a depending part for fitting against the inner side edge of the lower portion of the jaw part 3. This depending part of the jaw part 7 is formed with a V-shaped groove 8 at its lower edge. The upper end of the shank is provided with a seg-

mental gear 9 and a handle part 10 is formed with a segmental gear 11 at its lower end for engaging the gear 9, a pivot bolt 12 passing through the prongs of the part 2 and through the lower 5 enlarged end of the handle part 10 for pivotally connecting the handle part 10 to the forked part with the two gears meshing with each other. The handle part 1 curves outwardly and upwardly from the forked part 2 and this part 1 and the part 10 have flat upper ends 13.

Thus by moving the handle part 1 the segmental gears will turn the shank 4 on its pivot 5 to cause the jaw part 7 to engage the jaw part 3 or to grip the metal between the two jaw parts.

15 An elongated channel member 14 has one of its flanges longer than the other and the long flange is provided with a longitudinally extending slot 15 while the short flange is provided with a tapered hole 16. The flanges engage the ends of the jaw part 7 and a bolt 17 passes through one end of the jaw part 7 and through the tapered hole 16 of the short flange of the member 14. A bolt 18 extends from the opposite end of the jaw part 7 and passes through the slot 15 in the long flange of the member 14 and receives a wing nut 19. The inner edge of the member 14 is formed with a V-shaped rib 20 for engaging the groove 8 in the depending part of the jaw member 7 as more clearly shown in Figure 5. By loosening the nut 19 and pushing the long flange of the member 14 downwardly the rib of the member 14 can be released from the jaw 7, the tapered opening 16 through which the bolt 17 passes permitting this downward movement of the member 14. Then the member 14 can be swung upwardly to the position shown in Figure 4 after which the thumb nut is tightened to hold the member 14 in this position.

40 When the device is used for forming a single seam in a pair of roofing sheets, for instance, the member 14 is moved to the position shown in Figures 1, 2, 3, 5 and 6 and then the edges of the two sheets are gripped between the jaw 45 members by moving the handle member 10 away from the handle part 1 and then the tool is manipulated to make the single seam. Then when the double seam is to be made, following the formation of the single seam, the member 14 is moved to an inoperative position, shown 50 in Figure 4, which shortens the height of the jaw 7 and the tool is then used on the single seam in the same manner to form the single seam into a double seam.

55 It is thought from the foregoing description

that the advantages and novel features of the invention will be readily apparent.

It is to be understood that changes may be made in the construction and in the combination and arrangement of the several parts provided that such changes fall within the scope of the appended claims.

Having described the invention, what is claimed as new is:

1. A roofing tool comprising an elongated member having a handle part at its upper end and a forked part depending from the handle part, a transversely extending jaw having its center connected with the lower end of the forked part, a shank extending between the prongs of the forked part and pivoted to the prongs adjacent its lower end, a transversely extending jaw connected at the center to the lower end of the shank for cooperating with the first jaw, a second handle member having its lower end enlarged and forming a segmental gear and passing between intermediate portions of the prongs, a pivot passing through the prongs and through the enlarged part and the upper end of the shank having an enlarged part formed with a segmental gear meshing with the first gear.

2. A roofing tool comprising an enlarged member having a handle part at its upper end and a forked part depending from the handle part, a transversely extending jaw having its center connected with the lower end of the forked part, a shank extending between the prongs of the forked part and pivoted to the prongs adjacent its lower end, a transversely extending jaw connected at the center to the lower end of the shank for cooperating with the first jaw, a second handle member having its lower end enlarged and forming a segmental gear and passing between intermediate portions of the prongs, a pivot passing through the prongs and through the enlarged part and the upper end of the shank having an enlarged part formed with a segmental gear meshing with the first gear, a channel-shaped member having its flanges pivotally and movably connected with the end of the jaw carried by the shank, whereby said channel member can be moved to a position where it

will engage the lower edge of the last-mentioned jaw to permit the tool to be used in forming a single seam, and the member can be moved to an inoperative position whereby the tool can be used in forming a double seam.

3. In a roofing tool comprising handle forming members, jaw parts at the lower ends of such members and a member adjustably connected with one of the jaw parts which when positioned engaging the lower edge of such jaw parts will permit the tool to be used in forming a single seam and when moved to inoperative position will permit the tool to be used in forming a double seam.

4. In a roofing tool including a pair of jaw parts and handle parts connected therewith, a channel-shaped member having its flanges engaging the ends of one jaw part, one flange having a tapered hole therein and the other flange having a longitudinally extending slot therein, a bolt passing through one end of the jaw part and through the tapered hole, a bolt carried by the other end of the jaw part and passing through the slot, a nut on the last-mentioned bolt for holding the member in position extending along the lower edge of said jaw part or in a position where the member is out of engagement with the lower edge of said jaw part.

5. In a roofing tool including a pair of jaw parts and handle parts connected therewith, a channel-shaped member having its flanges engaging the ends of one jaw part, one flange having a tapered hole therein and the other flange having a longitudinally extending slot therein, a bolt passing through one end of the jaw part and through the tapered hole, a bolt carried by the other end of the jaw part and passing through the slot, a nut on the last-mentioned bolt for holding the member in position extending along the lower edge of such jaw part or in a position where the member is out of engagement with the lower edge of said jaw part, said jaw part having a groove in its lower edge and a bead on the upper edge of the channel member for engaging the groove when the channel member is in operative position.

QUINTAL A. PAQUE.
